C. J. RANDALL:
CIRCULATION AND EXHAUSTING APPARATUS FOR VULCANIZING.
APPLICATION FILED FEB. 5, 1916.

1,210,101.

Patented Dec. 26, 1916.

CHESTER J. RANDALL, OF NAUGATUCK, CONNECTICUT, ASSIGNOR TO THE GOODYEAR'S METALLIC RUBBER SHOE CO., A CORPORATION OF CONNECTICUT.

CIRCULATION AND EXHAUSTING APPARATUS FOR VULCANIZING.

1,210,101.

Specification of Letters Patent. Patented Dec. 26, 1916.

Application filed February 5, 1916. Serial No. 76,368.

To all whom it may concern:

Be it known that I, CHESTER J. RANDALL, a citizen of the United States, residing at Naugatuck, county of New Haven, and 5 State of Connecticut, have invented certain new and useful Improvements in Circulation and Exhausting Apparatus for Vulcanizing, of which the following is a full, clear, and exact description.

10 This invention relates to apparatus used in controlling the internal and external pressure exerted upon articles embodying rubber, rubber-like, or similar materials, during or prior to the process of vulcanization.

15 Rubber articles such as boots or shoes, designed to be subjected to a controllable differential of pressure treatment, are usually built upon hollow, perforated trees or forms.

20 The car carrying these forms with the articles to be vulcanized thereon, is run into a vulcanizer, in which the outside of the articles is subjected to controllable high pressure. The hollow frame of the car,

25 which communicates with the hollow forms, is connected to a low pressure pipe, whereby the inside of the articles is subjected to a lesser pressure than the outside, this differential of pressure serving to exhaust en-

30 trapped air, gases, fluids, and the like, from the articles. Usually both external pressure and heat are supplied to the articles by surrounding them in the vulcanizer with a heated fluid medium, such as CO₂, under pressure.

35 In practice, considerable leakage of the medium into the forms and car-frame occurs, so that, although the results obtained are desirable; namely, increased compacting 40 and densifying of the articles, yet the process is expensive, due to such leakage resulting in an appreciable loss of heat units and even waste of the medium itself. Furthermore this leakage is oftentimes so 45 great that suitable low pressure for the purpose, cannot be maintained in the forms.

50 My present invention obviates the above disadvantages by passing said leakage quickly back into the vulcanizer under such conditions that the proper degrees of differential pressure is maintained and also a circulation of the medium in the vulcanizer produced. As a result more uniform density and a more uniform degree of vulcanization throughout all parts of the rubber

articles, will be produced, than hitherto possible.

The invention can be readily understood from the following description, taken in connection with the accompanying drawing, 60 in which the figure is a sectional view with parts in elevation showing apparatus embodying my improvements.

In one embodiment of my invention, I employ a car 10 having a frame 11 which 65 is formed of communicating tubing, there being upstanding branch pipes 12 of this tubing to support a plurality of perforated hollow forms 13, of the usual and well-known type, with the articles, in the present 70 instance boots 14, built thereon. The car is mounted upon wheels 15 which facilitate it being run upon a track 16, into a vulcanizer 17 of the usual and well-known type. Heat and pressure are supplied to the articles in the vulcanizer through a suitable medium, such as CO₂, which enters the vulcanizer through a perforated inlet pipe 18. A low pressure pipe 19 enters the vulcanizer and is controlled by a valve 20, this 75 pipe having one or more branch pipes 21, each controlled by a valve 22 and adapted to be operatively connected with the frame of a corresponding car in the vulcanizer.

The parts above described are approximately the same as usually employed in the differential of pressure process of vulcanization.

My improvements consist in equipping such apparatus with devices for turning the 90 medium, which leaks into the forms and car-frame, back into the vulcanizer and simultaneously causing a circulation of the medium in the vulcanizer, as will now be described.

In carrying out the invention, I connect the exhaust pump 23 which creates low pressure in the forms through the pipe 19, with a preheater 24, by means of a pipe 25, said preheater being connected with the above 100 mentioned inlet pipe 18. Upon the pump being started and the valves 20 and 22 opened, any medium leaking into the forms and frame will be withdrawn through the pipe 19, by the pump 23, and urged by the latter in the shortest route and in minimum time back into the vulcanizer through the pipe 25, preheater 24 and pipe 18. Thus loss of CO₂, and loss of heat units, will be 105 reduced to a minimum, thereby decreasing 110

the expense of manufacturing under this process.

In further carrying out the invention, I provide a perforated outlet pipe 26 for the heat and pressure medium in the vulcanizer, this outlet pipe being also connected with the exhaust pump 23, as shown, and being controlled by a valve 27 located outside of the vulcanizer. The amount which the valve 27

- 10 is opened, determines the amount of the medium withdrawn from the vulcanizer and consequently permits of as much of the capacity of the pump being utilized for the purpose of exhausting the forms as is necessary to maintain a proper degree of low pressure in the forms to insure uniform density of the rubber articles. When the valve 27 is opened to any extent whatever, there will be created a circulation of the 20 medium in the vulcanizer through the car-frames and about the articles being vulcanized so that more uniform heat conditions and consequently greater uniformity in the degree of vulcanization throughout the articles in all parts of the vulcanizer, will be secured, than hitherto possible.

The operation of the apparatus in its most preferable form is as follows: The valve 20 is kept closed until it is desired to apply the 30 differential pressure, the apparatus prior to this serving to cause a circulation of the heat and pressure medium throughout the vulcanizer, the medium entering from the preheater through the inlet pipe 18, and being withdrawn through the outlet pipe 26 and pump 23 and discharged by the latter into the preheater 24 from which it passes into the inlet pipe 18. When it is desired to apply the differential pressure, the valve 40 27 is closed or partially closed. Then the valve 20 in the low pressure pipe is opened and the suction from the pump 23 allowed to act upon the interior of the forms. By leaving the valve 27 slightly open, circulation 45 may be continued in the vulcanizer, the amount of opening determining the degree of differential pressure exerted upon the articles during the remainder of the vulcanization process.

50 Although I have described one specific embodiment of the invention, I do not limit myself to the specific apparatus, or sequence of operation described, since a wide range 55 of modifications may be employed within the scope of the appended claims, in practising the invention.

Having thus described my invention, what I claim as new and desire to protect by Letters Patent is:

- 60 1. An apparatus of the class described, comprising a vulcanizer, a hollow form therein, means for exhausting the form, and means for directing the exhaust from the form into the vulcanizer.

65 2. An apparatus of the class described,

comprising a vulcanizer, means for admitting a fluid medium into the vulcanizer, a hollow form in the vulcanizer, means for exhausting the form and withdrawing some of said medium from the vulcanizer, and means for directing the exhaust from the form and said withdrawn medium into the vulcanizer.

3. An apparatus of the class described, comprising a vulcanizer, means for admitting a fluid medium into the vulcanizer, a hollow frame in the vulcanizer, hollow forms detachably mounted on and communicating with the frame, means for exhausting the forms and the frame, and means for directing the exhaust from the forms and frame together with any of the fluid medium which may leak into the forms and frame back into the vulcanizer.

4. An apparatus of the class described, comprising a vulcanizer, means for admitting a fluid medium into a vulcanizer, a hollow frame in the vulcanizer, hollow forms mounted on and communicating with the frame, an exhaust device, means establishing intake communication to the exhaust device from the frame and from the interior of the vulcanizer, and means establishing return communication from the exhaust device to the interior of the vulcanizer.

5. An apparatus of the class described, comprising a vulcanizer, means for admitting a fluid medium into the vulcanizer, a hollow frame in the vulcanizer, hollow forms mounted on and communicating with the frame, an exhaust device, means establishing intake communication to the exhaust device from the frame, means establishing intake communication to the exhaust device from the interior of the vulcanizer, a valve 105 for controlling the passage of the medium from the vulcanizer through the last named means, and means establishing return communication from the exhaust device to the interior of the vulcanizer.

6. An apparatus of the class described, comprising a vulcanizer, means for admitting a fluid medium under pressure thereinto, a hollow form therein, and means for exhausting the form and simultaneously causing a circulation of the pressure medium in the vulcanizer.

7. An apparatus of the class described, comprising a vulcanizer, a hollow form therein, means for exhausting the form, a 120 preheater, and means for directing the exhaust from the form through the preheater and into the vulcanizer.

8. An apparatus of the class described, comprising a vulcanizer, means for admitting a fluid medium into the vulcanizer, a hollow frame in the vulcanizer, hollow forms mounted on and communicating with the frame, means for exhausting the forms and the frame, a preheater, and means for 125 180

- directing the exhaust from the forms and frame together with any of the fluid medium which may leak thereinto through the preheater and into the vulcanizer.
9. An apparatus of the class described, comprising a vulcanizer, a hollow frame in the vulcanizer, hollow forms mounted on and communicating with the frame, an exhaust device, means establishing intake communication to the exhaust device from the
- 10

frame and from the interior of the vulcanizer, a preheater, means establishing outlet communication from the exhaust device to the preheater, and means establishing communication between the preheater and interior of the vulcanizer. 15

Signed at Naugatuck county of New Haven State of Connecticut this 31st day of January 1916.

CHESTER J. RANDALL.
